UNITED STATES PATENT OFFICE.

ALBERT G. KRUEGER AND FREDRICK W. THORPE, OF GREEN BAY, WISCONSIN.

PAPER-NAPKIN DISPENSER.

Application filed December 1, 1925. Serial No. 72,499.

The invention relates to paper napkin holders, and especially to the class of paper napkin dispensing devices.

The primary object of the invention is the provision of a device of this character, wherein the folded paper napkins are held within a receiver, so that said napkins can be extracted singularly from the open top thereof, the napkins being held in said receiver in stacked massed relation, and said mass automatically acted upon to advance or force the same upwardly in the receiver as each upmost napkin is taken from said receiver, thereby assuring a positive upward feed of the napkins during the use of the device.

Another object of the invention is the provision of a device of this character, wherein the receiver has mounted in its bottom pusher elements serving as a rest therefor, and due to the weight of said receiver and its contents thereon, cause the said pusher elements to automatically operate upon the massed paper napkins contained in the receiver to continuously feed the mass upwardly therein as the napkins are singly extracted or taken from the device.

A further object of the invention is the provision of a device of this character, wherein the construction thereof is novel in form, the paper napkins being readily and easily placed therein, and conveniently removed therefrom in successive single order.

A still further object of the invention is the provision of a device of this character, which is extremely simple in construction, thoroughly reliable and efficient in operation, strong, durable, possessing but few parts, positive in its operation, neat and attractive in appearance, most useful, and inexpensive to manufacture.

With these and other objects in view, the invention consists in the features of construction, combination and arrangement of parts, as will be hereinafter more fully set forth in detail, illustrated in the accompanying drawing, and pointed out in the claims hereunto appended, it being understood of course that changes, variations and modification can be made, as the form illustrated is the preferred embodiment, without departing from the spirit of the invention or sacrificing any of the advantages of the same.

In the accompanying drawing:

Figure 1, is a top plan view of the paper

napkin dispenser constructed in accordance with the invention.

Figure 2, is a vertical sectional view on the line 2—2 of Figure 1, looking in the direction of the arrow.

60

Figure 3, is an end elevation.

Similar reference characters indicate corresponding parts throughout the several views in the drawing.

Referring to the drawing in detail, A, 65 designates generally the body of the device, in which is adapted to be placed the stack of massed folded napkins made from paper sheets B, and this body is preferably made from sheet metal, including sides 5, ends 70 6, an open top 7, and an open bottom 8, respectively.

The open top 7, has inturned opposite side ledges 9, and likewise the open bottom is formed with similar side ledges 10. The 75 open bottom 8, also has formed at opposite ends the inturned ledges 11, from which are built upstanding vertical ears 12, for a purpose presently described.

Arranged at and working through the 80 open bottom 8, of the body A, is a pair of pusher elements including reversely disposed levers 13, and 14, respectively. Each lever 13, and 14, is formed with an outwardly bowed or curved rocker portion 15, adjacent to the outer hook end 16, which is hinged to its companion ear 12, and an inner upwardly or reversely curved end portion 17, the latter being adapted to contact and work against the lowermost napkin of the stacked mass 90 thereof contained within the body. The rocker portions 15, of the levers 13, and 14, rest upon a table top or other support carrying the dispenser when in use. The weight of the body A, and the contents thereof 95 causes pressure on the levers 13, and 14, so that these pusher elements will exert at their inner ends 17, an upward pressure upon the mass of paper napkins forcing the same upwardly in the body, and in this manner the uppermost napkin of the stack will be maintained against the top side ledges 9, at the open top 7, of said body.

The rocker portions 15, of the levers 13 and 14, are cut away at their inner edges as at 18, so that these levers can be assembled in their reversed overlapped relation to each other, and the action of one lever will not retard the movement of the other, as will be apparent. In other words these levers 13, 110

and 14, are free to move upwardly or downwardly independently of each other.

To fill the body A, with napkins the stack or mass thereof is inserted through the open top 7, of said body, so that when said mass of napkins is inserted in the body they will rest upon the inner end portions 17, of the levers 13, and 14. The rocker portions 15, of the levers are then brought to rest upon a table top or other support, and the weight of the body A, and the massed napkins B, therein will cause the pusher elements to automatically operate to force the napkins B, upwardly within the body, and maintain the uppermost napkin of the mass against the top ledges 9, in position to be conveniently extracted from the open top 7, of said body A.

It will be apparent that the napkins of the mass contained within the body A, can be freely extracted through the open top 7, singly in successive order, and said mass of napkins will be constantly maintained in the upper portion of the body.

What is claimed is:

1. A device of the character described, comprising a paper napkin holder, rocker elements swingingly connected with and projected inwardly and outwardly of the holder for supporting the same and active by the weight of said holder thereon to automatical-

ly advance the contents of the latter to dispensing position.

2. A device of the character described, comprising a napkin holder of substantially box form having an open top and bottom, and adapted to receive a stack of napkins, ears bent inwardly from the holder at opposite ends of its open bottom, opposed reversely disposed curved levers working through the open bottom of the holder for supporting the stack of napkins and said holder, and hook like terminals on the levers, and loosely engaged with the ears for swingingly connecting said levers with the holder. 45

3. A device of the character described, comprising a napkin holder open at its top and bottom, and adapted to receive a stack of napkins, opposed reversely disposed curved levers working through the open bottom of the holder for supporting the stack of napkins and said holder, and automatically advancing said napkins on the successive removal of the uppermost ones of the stack, means on the open top of the holder to normally retain the napkins therein, and inter-fitted connections between the ends of the holder at its bottom and the levers. 50

In testimony whereof we affix our signatures.

ALBERT G. KRUEGER.
FREDRICK W. THORPE.
